PARALLEL-MOTION-SUPPORTED PICKER STICK CHECK FOR LOOMS

John C. Crocker, Ware Shoals, S. C.

Application August 10, 1953, Serial No. 373,140

17 Claims. (Cl. 139—150)

This invention relates to looms, and more especially to an improved picker stick check associated with the usual parallel motion, this application being a continuation-in-part of my co-pending application, Serial Number 309,879, filed September 16, 1952, and entitled Parallel Tongue and Picker Stick Check for Looms, now Patent Number 2,655,183, issued October 13, 1953.

In said co-pending application, improved forms of parallel tongues are disclosed each of which is fixed to the inner edge of the picker stick and is carried by the parallel shoe and which has a substantially U-shaped portion on the lower end thereof whose opposite legs straddle and slidably engage a transverse shaft carried by the oscillating stand or parallel base and, in one form, a compression spring is disposed in the U-shaped portion of the tongue and engages the transverse shaft to urge the parallel shoe into engagement with the upper surface of the oscillating stand. In another form of the parallel tongue disclosed in said co-pending application, the usual type of spring actuated drum is connected to the outer edge of the picker stick by means of the usual heel strap to also serve for maintaining the parallel shoe in engagement with the upper surface of the oscillating stand.

Now, both forms of said spring means in said co-pending applications serve to check inward movement of the picker stick and the first form of spring means also serves to check outward movement of the picker stick. However, the effective checking action of the spring means of the first form above described is substantially the same with both inward and outward movements of the picker stick and, since the checking action of the spring means of the first form of the invention gradually increases as the picker stick moves either inwardly or outwardly, it has been found that the filling yarn or thread becomes slackened as the shuttle is boxed, due to the gradual slowing of the movement of the shuttle effected by the checking action of the spring means associated with the first form of parallel motion above described.

It is, therefore, the primary object of this invention to provide an improved picker stick check adapted to be associated with a parallel tongue of the character disclosed in said co-pending application which is so arranged as to effect gradually increasing checking pressure on the picker stick in the course of each inward or active stroke thereof and which, on the other hand, does not have any checking action on outward movement of the picker stick until the shuttle is substantially completely boxed or has substantially fully entered the corresponding shuttle box, and which picker stick check will then be effective to suddenly retard and check outward movement of the picker stick under relatively heavy pressure. The latter means described for checking outward movement of the picker stick not only serves to suddenly check movement of the shuttle into the corresponding shuttle box; thereby insuring that the filling yarn or thread is maintained under proper tension, but it also serves to prevent the picker on the upper end of the picker stick from being thrown against the lay end plate thereby

2

greatly increasing the usual life of a picker as compared to pickers heretofore used in association with the usual types of picker stick checks.

More specifically, it is an object of this invention to provide a picker stick check comprising a heel plate adapted to be secured to the outer edge of the curved lower portion of the picker stick and to also provide an extension on the parallel base with means for connecting opposite ends of a compression spring to said extension and to the lower end of the heel plate, respectively, whereby the compression spring is gradually compressed in the course of an inward or shuttle propelling stroke of the picker stick. Further, the lower end of a parallel tongue of the character disclosed in said co-pending application has a rigid frame member or strap member fixed thereto and projecting inwardly therefrom to which a resilient bumper is secured and which bumper is so positioned as to engage the lower surface of the parallel base immediately before the picker stick reaches the end of an outward stroke to thereby suddenly check outward movement of the picker stick and which, in so doing, permits the shuttle to become substantially fully boxed before movement thereof is checked and which, as above stated, also prevents the picker from engaging the lay end plate at the outer end of the corresponding shuttle box.

It is still another object of this invention to provide an improved picker stick check and parallel motion of the character described wherein all of the parts thereof may be used at either side of the loom; that is, at either end of the usual sword-supporting rocker shaft, without the necessity of making right-hand and left-hand parts.

Some of the objects of the invention having been stated, other objects will appear as the description proceeds, when taken in connection with the accompanying drawings, in which—

Figure 1 is a fragmentary elevation of the lower left-hand portion of a loom as though looking from the front of a loom and showing the parallel motion and the improved picker stick check in association therewith;

Figure 2 is an enlarged view of the outer end of the parallel motion embodying the improved picker stick check and looking at the left-hand side of the lower portion of Figure 1 with the compression spring broken away;

Figure 3 is an enlarged fragmentary plan view showing the picker stick in cross section and being taken substantially along line 3—3 in Figure 1;

Figure 4 is a longitudinal vertical sectional view taken along line 4—4 in Figure 3;

Figure 5 is a view similar to Figure 4, but showing the picker stick in an inward inclined position;

Figure 6 is a view similar to Figure 4, but showing a modified form of heel plate or heel spring anchor connected to the lower end of the picker stick and also showing another form of resilient arresting means;

Figure 7 is an outer end elevation looking at the left-hand side of Figure 6, but omitting the outer spring.

Referring more specifically to the drawings, the numeral 10 (Figure 1) indicates the loom frame, carrying the usual rocker shaft 11 on which is secured the hub 9 of an improved oscillating stand or parallel base broadly designated at 12 in the first form of the invention shown in Figures 1 to 5, inclusive. The oscillating stand or parallel base 12 has a flat-topped outwardly extending plate portion 13 integral therewith and the oscillating stand or parallel base 12 may be of conventional construction with the exception of a parallel extension 13a integral with, and projecting outwardly from, the outer end of the plate portion 13. The purpose of the extension 13a will be later described. Since the usual type of spring actuated drum is not used with the improved picker stick check, it should be noted that the hub 9 is substantially

concentric with the plate portion 13 and picker stick 15, so that the parallel motion may be used at either end of the rocker shaft, thereby obviating the use of right-hand and left-hand parts.

The plate portion 13 of the parallel base or oscillating stand 12 is provided with the usual opening 14 through which the lower portion of a conventional picker stick 15 loosely extends. The lower portion of the picker stick 15 also loosely extends through an opening 19 in a conventional parallel shoe 16 having a curved lower surface 17 which rocks longitudinally upon the oscillating stand or parallel base 12 and also oscillates laterally therewith, as is customary. The picker stick 15 is fixed to the parallel shoe 16 by a bolt 20 which penetrates an upwardly projecting portion or shank 21 integral with the shoe 16 and which bolt also penetrates one form of an improved combination heel plate and spring connector. Of course, the upper portion of the improved tongue, similar to that disclosed in said co-pending application, is interposed between the projection or shank 21 of the parallel shoe 16 and the picker stick 15.

The picker stick 15 is actuated by any suitable means such as a lug strap 24 connected with the usual picking mechanism, not shown. In Figures 1 and 4, the picker stick is shown in an outer inclined position; that is, in a position outwardly of the neutral or substantially vertical position and to which outwardly inclined position the picker stick is moved by impact of a shuttle, not shown. In Figure 5, the picker stick is shown in an inwardly inclined position to which it is moved by the lug strap 24 for throwing the shuttle across the lay in the usual manner.

The improved parallel tongue, broadly designated at 30, is of substantially the same construction as the parallel tongue disclosed in said co-pending application and comprises a substantially U-shaped yoke portion 31 having spaced parallel upwardly extending arms or legs 32 and 33, the leg 33 being substantially longer than the leg 32 and extending upwardly through the opening 14 in the plate portion 13 of the parallel base 12 and also extending upwardly through the opening 19 in the parallel shoe 16 and being suitably secured to the inner surface of the picker stick 15 by the bolt 20. The leg 33 of the parallel tongue 30 actually forms a J-shaped member and is preferably provided with flanges 34 on opposed sides thereof between which the lower portion of the picker stick 15 fits. The upper end of the inner arm 32 of the U-shaped or yoke portion 31 of the parallel tongue 30 preferably terminates against or in closely spaced relationship to the lower curved surface 17 of the parallel shoe 16.

It is evident that the position of the picker stick and the parallel tongue 30 may be adjusted relative to the parallel shoe 16 by means of a set screw 35 which threadably penetrates the upper portion of the upwardly extending projection or portion 21 of the parallel shoe 16 and bears against the corresponding surface of the leg or arm 33 of the parallel tongue 30, the adjustment screw 35 being maintained in the proper position by a lock nut 36. The two legs or arms 32 and 33 of the tongue 30 form an opening in which a bushing 41 is slidably and oscillatably mounted on a transverse shaft 42 fixed in opposite walls of the opening 14 in the oscillating stand or parallel base 12.

The tongue 30 differs from the tongues shown in said co-pending applications in that the lower end of the U-shaped portion 31 thereof has a rigid strap member 45 suitably secured thereto, as by a bolt 46, the head of which is spaced beneath the bushing 41 to permit the outer portion of the shoe 16 to move upwardly away from the flat upper surface of the plate portion 13 of the oscillating stand or parallel base 12 as it moves to the inwardly inclined position as shown in Figure 5, and to also permit the inner end of the shoe 16 to move away from the flat upper surface of the plate portion

13 of the oscillating stand 12 as the picker stick 15 is moved to the outwardly inclined position shown in Figures 1 and 4. The lower portion of the U-shaped portion 31 of the tongue 30 is cut away to form a notch 47 in which an upturned portion 50 at the outer end of the rigid strap member 45 is positioned to prevent the strap member 45 from pivoting about the bolt 46.

The strap member 45 is a part of the means for checking outward movement of the picker stick, and has a longitudinally extending adjustment slot 51 in the inner end thereof which is penetrated by a screw portion 52 of a resilient bumper supporting plate 53 spaced above the plate or rigid strap member 45 and to the upper surface of which a resilient bumper 54 is suitably secured, as by bolts 55. In the present instance, the screw portion 52 of the bumper supporting plate 53 is shown in the form of a screw whose head is suitably secured to the lower surface of the plate 53 and the screw portion 52 has a pair of lock nuts 56 and 57 threadably mounted thereon and engaging the respective upper and lower surfaces of the strap member 45 to maintain the bumper supporting plate 53 in the desired adjusted position.

The bumper 54 is shown in Figure 4 as though made from rubber or other resilient material and it is to be distinctly understood that any suitable resilient means may be supported on the bumper supporting plate 53 for engaging the lower surface of the plate portion 13 of the oscillating stand or parallel base 12 in the course of outward swinging movement of the picker stick 15. For example, a compression spring may be substituted for the bumper 54, as will be later described with reference to Figure 6, for engaging the lower surface of the plate portion 13 of the oscillating stand 12 in the course of outward movement of the picker stick 15. The resilient bumper 54 should be so adjusted that, when the picker stick is in the substantially vertical or neutral position, the upper end of the bumper 54 is spaced slightly from the lower surface of the plate portion 13 of the oscillating stand or parallel base 12 so that, as the picker stick 15 is swung outwardly under impact of the shuttle, the bumper 54 will not interfere with the boxing of the shuttle and will not retard or check movement of the picker stick 15 until the shuttle is substantially boxed, whereupon the bumper 54 will then engage the lower surface of the plate portion 13 of the oscillating stand 12 and be compressed slightly thereby to suddenly arrest or check the movement of the shuttle and to thereby insure that the filling thread or yarn remains taut throughout the width of the fabric being woven. This is particularly important when weaving with rayon or silk yarns. Also, as heretofore stated, the checking action of the bumper 54 engaging the lower surface of the plate portion 13 of the oscillating stand 12 is such that the picker, not shown, is prevented from being driven against the usual lay end plate as the shuttle is boxed.

Now, in order to apply gradually increasing pressure to the picker stick 15 in checking inward movement of the same, a compression spring 62 is employed which is disposed outwardly of the picker stick and whose lower end engages an outwardly or downwardly inclined tab portion 63 on an improved heel plate 64 whose lower portion is curved to conform to the usual curved lower end 15a of the picker stick 15 and whose upper portion is penetrated by the bolt 20 for securing the heel plate 64 against the outer edge of the picker stick 15. The upper portion of the heel plate 64 is provided with a pair of spaced inwardly projecting flanges 65 which engage opposite sides of the picker stick 15 to assist in properly positioning the heel plate 64 on the picker stick 15. The lower end of the compression spring 62 may be connected to the tab portion 63 on the lower end of the heel plate 64 by any suitable means, and, in the present instance, the tab 63 has an outwardly projecting finger or pilot 66 integral therewith about which a few turns of the spring 62 are positioned. A few turns at the upper end of the com-

pression spring 62 encircle a pilot portion or finger 67.

The upper pilot member 67 has an enlarged medial portion 71 integral therewith which is preferably polygonally-shaped for the reception of an open-end wrench or the like to facilitate adjustment of the pilot 67 relative to the extension 13a on the oscillating stand 12 and to thereby facilitate adjustment of the compression spring 62. The threaded upper portion or shank 70 of the upper spring pilot member 67 threadably penetrates said extension 13a and is held in adjusted position by means of a lock nut 72 engaging the upper surface of the extension 13a on the oscillating stand 12.

It is thus seen that in the course of inward swinging movement of the picker stick 15, the compression spring 62 exerts gradually increasing resilient resistance to the inward movement of the picker stick 15 as it is compressed as shown in Figure 5 to thereby resiliently check inward movement of the picker stick 15.

Modified or second form of the invention

Referring to Figures 6 and 7, a modified form of the invention is illustrated in which all of the parts thereof, with the exception of a second form of heel plate, a washer engaging the outer surface of the picker stick, and a spring being used to check outward movement of the picker stick, are identical to the parts heretofore described with respect to Figures 1 to 5, inclusive. Therefore, those parts in Figures 6 and 7, which are substantially the same as parts shown in Figures 1 to 5, inclusive, shall bear the same reference characters with the prime notation added.

In Figures 6 and 7, the heel plate is designated at 74 and its upper end terminates in substantially spaced relation to the bolt 20'. The relatively short heel plate 74 is suitably secured to the heel or outer edge of the picker stick, as by a lag screw 75; the lower end of the heel plate 74 has a spring supporting projection or tab 76 integral therewith and projecting outwardly therefrom which is provided with a lower spring pilot member 77. A few turns at the lower end of the compression spring 62' are mounted upon the pilot 77 and the lower end of the compression spring 62' bears against the spring engaging portion 76 of the heel plate 74. Of course, when using the modified form of heel plate 74, a conventional type of picker stick washer 80 is employed which engages the outer edge of the picker stick and which is penetrated by the bolt 20'. Both types of heel plates 64 and 74 serve the same purpose and a further description of the operation of the structure shown in Figures 6 and 7 is therefore deemed unnecessary.

It is also to be observed in Figure 6 that a compression spring 82 is substituted for the rubber bumper 54. In Figure 6, the plate 53' has a threaded portion 83 thereon whose threads have a lead and diameter corresponding to the spring 82 so the spring 82 is secured on the plate 53' by being threaded onto the threaded portion 83. Of course, the spring 82 serves the same purpose as the bumper 54 and a further description thereof is deemed unnecessary.

It is thus seen that I have provided improved means for checking inward and outward swinging movement of the picker stick and wherein the shuttle may be substantially fully boxed before the outward check means is effective and whereupon the outward check means then suddenly resiliently checks the outward movement of the picker stick to thereby maintain the filling thread or yarn under proper tension and to prevent the usual picker from engaging the usual lay end plate.

In the drawings and specification there has been set forth a preferred embodiment of the invention and although specific terms are employed, they are used in a generic and descriptive sense only, and not for purposes of limitation, the scope of the invention being defined in the claims.

I claim:

1. An improvement in a parallel motion for picker

sticks in a loom having an oscillatable parallel provided with an elongated longitudinally extending slot through which the picker stick extends and having an oscillatable shoe mounted on the parallel and having an elongated slot through which the picker stick passes and means for securing the picker stick to the shoe; the improvement comprising a transversely disposed member spanning the slot in the parallel, a member secured to the stick and extending through the slots in the shoe and parallel and having a transverse opening in its lower end penetrated by said transverse member, resilient means disposed between the outer end of the parallel and the lower end of the picker stick tending to move the upper end of the picker stick away from the central portion of the loom and second resilient means secured to the member secured to the picker stick and engaging the lower surface of the parallel upon the upper end of the picker stick approaching the end of its travel away from the central portion of the loom.

2. An improvement in a parallel motion for picker sticks in a loom having an oscillatable parallel provided with a longitudinally extending slot through which the picker stick extends and having an oscillatable shoe mounted on the parallel and having a slot through which the picker stick extends and means for securing the picker stick to the shoe; the improvement comprising resilient means disposed between the outer end of the parallel and the lower end of the picker stick biasing the upper end of the picker stick away from the central portion of the loom, and other resilient means disposed between the lower end of the picker stick and an inner portion of the parallel and engageable with the parallel upon the upper end of the picker approaching the end of its outward travel for arresting outward travel of the upper end of the picker stick.

3. An improvement in a parallel motion for picker sticks in a loom having an oscillatable parallel provided with a longitudinally extending slot through which the picker stick extends and having an oscillatable shoe mounted on the parallel and having a slot through which the picker stick extends and means for securing the picker stick to the shoe; the improvement comprising resilient means disposed between the outer end of the parallel and the lower end of the picker stick biasing the upper end of the picker stick away from the central portion of the loom, a rigid member, means connecting one end of the rigid member to the lower end of the picker stick, said rigid member extending inwardly below the parallel, and resilient means secured on the inner end of the rigid member for engaging the parallel upon the upper end of the picker stick approaching the end of its outward travel away from the central portion of the loom for arresting outward travel of the picker stick.

4. An improvement in a parallel motion for a picker stick and a loom having an oscillatable parallel base provided with an elongated longitudinally extending slot through which the picker stick extends and having an oscillatable shoe mounted on the parallel base and having an elongated slot through which the picker stick passes and means for securing the picker stick to said shoe; the improvement comprising a bolt spanning the slot in the parallel, a J-shaped member disposed in said slots and having its longer leg secured to the picker stick and shoe and having the lower portion of the longer leg and the shorter leg disposed on both sides of the bolt in the parallel, inward checking means comprising a heel plate secured to the outer edge of said picker stick relative to the tongue and having an outwardly projecting portion on the lower end thereof adjacent the lower end of the picker stick, an extension on the outer end of said parallel base disposed outwardly of the outer end of said parallel shoe, a compression spring, means connecting one end of the compression spring to the extension, and means connecting the other end of the compression spring to said heel plate, a rigid member

secured to the lower end of said J-shaped tongue and extending inwardly therefrom away from the picker stick, and a resilient bumper carried by said rigid member and being so positioned as to engage the lower surface of the parallel base in the course of outward swinging movement of the picker stick for checking movement thereof and whereby inward movement of the picker stick is checked by the compression spring.

5. In a loom having a parallel motion including a parallel base having a slot therethrough, a parallel shoe having a slot therethrough, a picker stick secured to the parallel shoe and extending through said slots and terminating below said parallel base, a rigid member disposed beneath the parallel base, means securing one end of the rigid member to the inner edge and lower end of the picker stick, a resilient bumper carried by the rigid member and being spaced inwardly from the picker stick and being adapted to engage the lower surface of the parallel base in the course of outward swinging movement of the picker stick, a compression spring disposed outwardly of the picker stick, means connecting the lower end of the compression spring to the lower end of said picker stick, and means connecting the upper end of the compression spring to the outer end of said parallel base whereby said compression spring offers gradually increasing resistance to inward movement of the picker stick during the course of inward swinging movement thereof.

6. In a loom having a parallel motion including a parallel base having a slot therethrough, a parallel shoe having a slot therethrough, a picker stick secured to the parallel shoe and extending through said slots and terminating below said parallel base, a rigid member disposed beneath the parallel base, means securing one end of the rigid member to the inner edge and lower end of the picker stick, a resilient bumper carried by the rigid member and being spaced inwardly from the picker stick and being adapted to engage the lower surface of the parallel base in the course of outward swinging movement of the picker stick, a compression spring disposed outwardly of the picker stick, means connecting the lower end of the compression spring to the lower end of said picker stick, means connecting the upper end of the compression spring to the outer end of said parallel base whereby said compression spring offers gradually increasing resistance to inward movement of the picker stick during the course of inward swinging movement thereof, said means connecting the lower end of the compression spring to the picker stick comprising a relatively thin heel plate conforming substantially to the shape of the lower end of the picker stick, means securing said heel plate to the outer edge of the picker stick, an outwardly projecting portion on the lower end of said heel plate, and a pilot projecting from the outwardly projecting portion of said heel plate on which the lower end of said compression spring is mounted.

7. In a loom having a parallel motion including a parallel base having a slot therethrough, a parallel shoe having a slot therethrough, a picker stick secured to the parallel shoe and extending through said slots and terminating below said parallel base, a rigid member disposed beneath the parallel base, means securing one end of the rigid member to the inner edge and lower end of the picker stick, a resilient bumper carried by the rigid member and being spaced inwardly from the picker stick and being adapted to engage the lower surface of the parallel base in the course of outward swinging movement of the picker stick, a compression spring disposed outwardly of the picker stick, means connecting the lower end of the compression spring to the lower end of said picker stick, means connecting the upper end of the compression spring to the outer end of said parallel base whereby said compression spring offers gradually increasing resistance to inward movement of the picker stick during the course of inward swinging movement thereof, said means connecting the lower end of the com-

pression spring to the picker stick comprising a relatively thin heel plate conforming substantially to the shape of the lower end of the picker stick, means securing said heel plate to the outer edge of the picker stick, an outwardly projecting portion on the lower end of said heel plate, a pilot projecting from the outwardly projecting portion of said heel plate on which the lower end of said compression spring is mounted, said means connecting the upper end of the compression spring to said parallel base including a pilot member adapted to be encircled by the upper portion of said compression spring, said pilot member having an enlarged portion thereon against which the upper end of said compression spring seats, a threaded portion on said pilot member threadably penetrating the outer end of said parallel base, and a lock nut threadably mounted on the threaded portion for maintaining the pilot member in adjusted position relative to the parallel base.

8. In a loom having a parallel motion including a parallel base having a slot therethrough, a parallel shoe having a slot therethrough, a picker stick secured to the parallel shoe and extending through said slots and terminating below said parallel base, a rigid member disposed beneath the parallel base, means securing one end of the rigid member to the inner edge and lower end of the picker stick, a resilient bumper carried by the rigid member and being spaced inwardly from the picker stick and being adapted to engage the lower surface of the parallel base in the course of outward swinging movement of the picker stick, a compression spring disposed outwardly of the picker stick, means connecting the lower end of the compression spring to the lower end of said picker stick, means connecting the upper end of the compression spring to the outer end of said parallel base whereby said compression spring offers gradually increasing resistance to inward movement of the picker stick during the course of inward swinging movement thereof, said means connecting the upper end of the compression spring to said parallel base including a pilot member adapted to be encircled by the upper portion of said compression spring, said pilot member having an enlarged portion thereon against which the upper end of said compression spring seats, a threaded portion on said pilot member threadably penetrating the outer end of said parallel base, and a lock nut threadably mounted on the threaded portion for maintaining the pilot member in adjusted position relative to the parallel base.

9. In a loom having a parallel motion including a parallel base having a slot therethrough, a parallel shoe having a slot therethrough, a picker stick secured to the parallel shoe and extending through said slots and terminating below said parallel base, a rigid member disposed beneath the parallel base, means securing one end of the rigid member to the inner edge and lower end of the picker stick, a resilient bumper carried by the rigid member and being spaced inwardly from the picker stick and being adapted to engage the lower surface of the parallel base in the course of outward swinging movement of the picker stick, a compression spring disposed outwardly of the picker stick, means connecting the lower end of the compression spring to the lower end of said picker stick, means connecting the upper end of the compression spring to the outer end of said parallel base whereby said compression spring offers gradually increasing resistance to inward movement of the picker stick during the course of inward swinging movement thereof, said means connecting the lower end of the compression spring to the picker stick comprising a relatively thin heel plate conforming substantially to the shape of the lower end of the picker stick, means securing said heel plate to the outer edge of the picker stick, an outwardly projecting portion on the lower end of said heel plate, a pilot projecting from the outwardly projecting portion of said heel plate on which the lower end of said compression spring is mounted, said means connect-

ing the upper end of the compression spring to said parallel base including a pilot member adapted to be encircled by the upper portion of said compression spring, said pilot member having an enlarged portion thereon against which the upper end of said compression spring seats, a threaded portion on said pilot member penetrating the outer end of said parallel base, and a lock nut threadably mounted on the threaded portion for maintaining the pilot member in adjusted position relative to the parallel base.

10. In a loom having a parallel motion including a parallel base having a slot therethrough, a parallel shoe having a slot therethrough, a picker stick secured to the parallel shoe and extending through said slots and terminating below said parallel base, a rigid member having a lateral projection disposed beneath the parallel base, a transverse member mounted in the slot in the parallel base on which the rigid member has pivotal and sliding movement, means securing one end of the rigid member to the picker stick adjacent the inner edge and lower end thereof, and a resilient bumper carried by the rigid member and being spaced inwardly from the picker stick and being adapted to engage the lower surface of the parallel base as the picker stick approaches the limit of an outward stroke.

11. In a loom having a parallel motion including a parallel base having a slot therethrough, a parallel shoe having a slot therethrough, a picker stick secured to the parallel shoe and extending through said slots and terminating below said parallel base, a rigid member having a lateral projection disposed beneath the parallel base, a transverse member mounted in the slot in the parallel base on which the rigid member has pivotal and sliding movement, means securing one end of the rigid member to the picker stick adjacent the inner edge and lower end thereof, a resilient bumper carried by the rigid member and being spaced inwardly from the picker stick and being adapted to engage the lower surface of the parallel base as the picker stick approaches the limit of an outward stroke, and means for adjusting said resilient bumper on said rigid member toward and away from said picker stick.

12. In a loom having a parallel motion including a parallel base having a slot therethrough, a parallel shoe having a slot therethrough, a picker stick secured to the parallel shoe and extending through said slots and terminating below said parallel base, a rigid member disposed beneath the parallel base, means securing one end of the rigid member to the picker stick adjacent the inner edge and lower end thereof, a resilient bumper carried by the rigid member and being spaced inwardly from the picker stick and being adapted to engage the lower surface of the parallel base as the picker stick approaches the limit of an outward stroke, and means for adjusting the resilient bumper toward and away from said rigid member to vary the time at which the bumper engages the parallel base relative to the position of the picker stick as it approaches the limit of an outward stroke.

13. In a loom having a parallel motion including a parallel base having a slot therethrough, a parallel shoe having a slot therethrough, a picker stick secured to the parallel shoe and extending through said slots and terminating outwardly of the picker stick, means connecting the lower end of the compression spring to the lower end of said picker stick, means connecting the upper end of the compression spring to the outer end of said parallel base whereby said compression spring offers gradually increasing resistance to inward movement of the picker stick during the course of inward movement thereof, said means connecting the lower end of the compression spring to the picker stick comprising a relatively thin heel plate conforming substantially to the shape of the lower end of the picker stick, means securing said heel plate to the outer edge of the picker stick, an outwardly projecting portion on the lower end of said heel plate, a pilot projecting from the outwardly projecting portion of said heel plate on which the lower end of said compression spring is mounted, said means connecting the upper end of the compression spring to said parallel base including a pilot member adapted to be encircled by the upper portion of said compression spring, said pilot member having an enlarged portion thereon against which the upper end of said compression spring seats, a threaded portion on said pilot member threadably penetrating the outer end of said parallel base, and a lock nut threadably mounted on the threaded portion for maintaining the pilot member in adjusted position relative to the parallel base.

14. In a loom having a parallel motion including a parallel base having a slot therethrough, a parallel shoe having a slot therethrough, a picker stick secured to the parallel shoe and extending through said slots and terminating below said parallel base, a compression spring disposed outwardly of the picker stick, means connecting the lower end of the compression spring to the lower end of said picker stick, means connecting the upper end of the compression spring to the outer end of said parallel base whereby said compression spring offers gradually increasing resistance to inward movement of the picker stick during the course of inward movement thereof, said means connecting the upper end of the compression spring to said parallel base including a pilot member adapted to be encircled by the upper portion of said compression spring, said pilot member having an enlarged portion thereon against which the upper end of said compression spring seats, a threaded portion on said pilot member threadably penetrating the outer end of said parallel base, and a lock nut threadably mounted on the threaded portion for maintaining the pilot member in adjusted position relative to the parallel base.

15. In a loom having a parallel motion including a parallel base having a slot therethrough, a parallel shoe having a slot therethrough, a picker stick secured to the parallel shoe and extending through said slots and terminating below said parallel base, a compression spring disposed outwardly of the picker stick, means connecting the lower end of the compression spring to the lower end of said picker stick, means connecting the upper end of the compression spring to the outer end of said parallel base whereby said compression spring offers gradually increasing resistance to inward movement of the picker stick during the course of inward movement thereof, said means connecting the upper end of the compression spring to said parallel base including a pilot member adapted to be encircled by the upper portion of said compression spring, said pilot member having an enlarged portion thereon against which the upper end of said compression spring seats, a threaded portion on said pilot member threadably penetrating the outer end of said parallel base, and a lock nut threadably mounted on the threaded portion for maintaining the pilot member in adjusted position relative to the parallel base.

16. An improvement in a parallel motion for looms wherein said loom has an oscillatable rocker shaft and said parallel motion includes a parallel shoe having a slot therethrough and a picker stick secured to said shoe and extending through said slot; said improvement comprising a parallel base having a hub adapted to be fixed on said rocker shaft, a plate portion integral with said hub and extending outwardly therefrom, said plate portion being substantially concentric with said hub, said parallel shoe being adapted to rest upon said plate portion and to oscillate parallel to the axis of said shaft, said plate portion having a slot therethrough through which said picker stick also extends, a rigid member disposed beneath the plate portion of the parallel base, means securing one end of the rigid member to the inner edge and lower end of the picker stick, a resilient bumper carried by the rigid member and being spaced inwardly from the picker stick and being adapted to engage the lower surface of the parallel base in the course of out-

ward swinging movement of the picker stick, a compression spring disposed outwardly of the picker stick, means connecting the lower end of the compression spring to the lower end of said picker stick, and means connecting the upper end of the compression spring to the outer end of said parallel base whereby said compression spring offers gradually increasing resistance to inward movement of the picker stick during the course of inward swinging movement thereof.

17. In a loom having a parallel motion including a 10 parallel base having a slot therethrough, a parallel shoe having a slot therethrough, a picker stick secured to the parallel shoe and extending through said slot and terminating below said parallel base, a rigid member having a lateral projection disposed beneath the parallel base, 15 a transverse member mounted in the slot in the parallel base on which the rigid member has pivotal and sliding

movement, means securing one end of the rigid member to the picker stick adjacent the inner edge and lower end thereof and a resilient bumper carried by the rigid member and being spaced inwardly from the picker stick and being adapted to engage the lower surface of a parallel base as the picker stick approaches the limit of an outward stroke.
